UNIVERSAL JOINT

Raymond E. Stokely, Rockford, Ill., assignor to Borg-Warner Corporation, Chicago, Ill., a corporation of Illinois

Filed Jan. 3, 1964, Ser. No. 78,048

Term of patent 14 years

(Cl. D55—1)

The sides opposite those shown in FIGURES 1, 2 and 3 are mirror images thereof.

I claim:

The ornamental design for a universal joint, substantially as shown and described.
